UNITED STATES PATENT OFFICE.

JOHN O'ROURKE, OF BROOKLYN, NEW YORK.

TUBE-EXPANDER.

SPECIFICATION forming part of Letters Patent No. 593,779, dated November 16, 1897.

Application filed May 15, 1897. Serial No. 636,621. (No model.)

To all whom it may concern:

Be it known that I, JOHN O'ROURKE, of Brooklyn, in the county of Kings and State of New York, have invented a new and useful 5 Improvement in Tube-Expanders, of which the following is a specification.

My invention relates to an improvement in tube-expanders in which provision is made for operating the casing which carries the 10 expanding-rollers by means of a ratchet and lever, while the expanding-spindle is under the control of a screw-feed to advance it.

A practical embodiment of my invention is represented in the accompanying drawings, 15 in which—

Figure 1 is a view of the expander in side elevation, the handle of the ratchet-lever being broken away. Fig. 2 is a view of the 20 same in longitudinal section; and Fig. 3 is an end view looking from the left toward the right, as represented in Figs. 1 and 2.

The casing which carries the expanding-rollers is denoted by A. It is made tubular, as is usual, to permit the expanding-spindle 25 B to pass centrally through it. The expanding-rollers C, three in number as here shown, have their journals or trunnions c c' the former mounted in radial slots a at the inner ends of the roller-pockets a' in the casing A. 30 and the latter, c', mounted in radial slots c² in an end cap A, secured snugly to the end of the casing A by screws a².

The forward portion of the casing A is reduced in diameter, and there is keyed thereon 35 a ratchet-toothed wheel D. The key for holding, the ratchet D to the casing is denoted by d.

An operating-lever E is bifurcated at its 40 end to receive between the branches e e' the ratchet-wheel D, and is further provided with a bore e², extending through the branches e e', for the reception of the reduced portion of the casing A.

It is intended that the bifurcated end of 45 the lever E shall work in a rotary direction on the casing A with freedom, but without any unnecessary play beyond that which is required to permit it a free rotary movement. A spring-actuated pawl F is pivoted between 50 the branches e e' of the lever, as at f, the spring f' serving to hold its operating end

normally in contact with the ratchet-teeth on the wheel D.

A guard G is mounted loosely on the casing A intermediate of the lever E and the 55 larger rear portion of the casing, and is provided with rearwardly-projecting flanges g g', spaced from the casing A sufficiently to permit the end of a tube to be expanded to enter between their inner faces and the exterior of the casing and to abut against the front plate (not shown) to hold the expanding-rollers C in their proper relation to the opening in the front plate in which the tube 60 is to be expanded.

To the front end of the casing A there is fixed a forwardly-projecting exteriorly-screw-threaded sleeve H, the rear end of said sleeve being adapted to receive within it the front 65 end of the casing A and serving to hold the 70 operating-lever E in position on the casing when it (the said sleeve) is fastened in position. The fastening consists in the present instance of one or more set-screws h.

An interiorly-screw-threaded feed-sleeve I 75 is adapted to screw onto the sleeve H, and is conveniently provided with sockets i for the reception of a spanner-wrench to turn the sleeve I. The outer end of the sleeve I is provided with an opening i' through it of 80 sufficient diameter to permit the expanding-spindle to be inserted centrally within the sleeve H and tubular casing A, and said expanding-spindle B is caused to move longitudinally along an axial line, together with 85 the feed-sleeve I, by a swivel connection which is made in the present instance by a pair of cap-pieces K K', each provided with a half-socket of such diameter as to loosely fit the reduced portions b, b', and b² of the spindle B. The cap-pieces K K' may be secured 90 in position to complete the spindle-embracing socket by means of set-screws k k', which extend through them into the end of the feed-sleeve I. The several reduced portions—in 95 the present case the three hereinabove referred to denoted by b b' b²—are provided for the purpose of adjusting the expanding-spindle to different sizes of tubes, thereby materially enlarging the field of usefulness 100 for the expander while maintaining the movement of the feed-sleeve I within the limits

required for expanding a tube of any one given size.

- In order to positively determine the extent to which the expanding-spindle B shall be 5 permitted to spread the expanding-rollers and thereby prevent any liability of expanding the tube to a greater or less extent than is most advisable, I provide a stop-nut L on the sleeve H, against which the feed-sleeve 10 will abut when it reaches the limit of its intended movement. The stop-nut L may be adjusted along the sleeve H to give the feed-sleeve a greater or less movement, as may be required.
- 15 In operation, when the expander has been placed in position, with the end of the tube to be expanded surrounding that portion of the casing where the expanding-rollers are located, the expanding-spindle B is forced 20 rearwardly by turning the sleeve I, and the casing A, carrying the expanding-rollers, is caused to rotate by the reciprocating movement of the operating-lever E. The forcing inwardly of the spindle B and the rotary 25 movement of the casing A will be continued until the sleeve I reaches the limit of its feed movement, determined by the stop-nut L, when the expander may be removed by re-turning the sleeve I to its forward position, 30 thereby withdrawing the expanding-spindle and permitting the expanding-rollers to collapse.
- In case of any failure on the part of the 35 ratchet-lever to operate or in case the position be such that the operation of the expander by the ratchet would be inconvenient or impracticable the expander may still be operated in the manner heretofore common by

rotating the expanding-spindle B, holes b³ being provided in its head for the purpose of 40 inserting an operating-bar. When the expanding-rollers are operated in this manner by the expanding-spindle, the feed may be effected in the same manner as when using the ratchet-lever D. 45

What I claim is—

1. A tube-expander comprising a tubular casing carrying the expanding - rollers, a ratchet-toothed wheel secured to the casing, an operating-lever loosely embracing the casing and carrying a pawl, a screw - threaded sleeve secured to the casing in axial alignment therewith, an expanding-spindle and a feed-sleeve swiveled to the expanding-spindle and engaged with the first - named sleeve, 55 substantially as set forth.

2. A tube-expander comprising a casing carrying expanding-rollers, means for rotating the casing, a screw-threaded sleeve secured to the casing, a feed-sleeve engaged 60 with the aforesaid sleeve, an expanding-spindle, a swivel connection between the expanding-spindle and feed-sleeve, and an adjustable stop to limit the movement of the feed-sleeve, substantially as set forth. 65

3. A tube-expander comprising expanding-rollers and their support, means for rotating the roller - support, an expanding - spindle, means for feeding it into engagement with the rollers and means for connecting the feed 70 device to the expanding-spindle at intervals along the spindle, substantially as set forth.

JOHN O'ROURKE.
